(57) **CLAIM**

The ornamental design for a contoured electric head shaver, as shown and described.

DESCRIPTION

FIG. 1 is a front top perspective view of a contoured electric head shaver showing my new design;

FIG. 2 is a front bottom perspective view thereof;

FIG. 3 is a top plan view thereof;

FIG. 4 is a bottom plan view thereof;

FIG. 5 is a left side view thereof, the right side being the mirror image thereof;

FIG. 6 is a rear end elevational view thereof, and,

FIG. 7 is a front end elevational view thereof.

The broken lines shown in the drawings illustrate portions of the article and form no part of the claimed design.
